PACKAGING MACHINE

Edward S. Killian, Akron, and Lawrence Pov-
lacs, Jr., East Akron, Ohio, assignors, by mesne
assignments, of thirty-seven and one-half per
cent to James Tyrrell, as trustee, and twenty-
five per cent to Perry H. Stevens, both of Akron,
Ohio

Application December 24, 1937, Serial No. 181,592

5 Claims. (Cl. 226—2)

- This invention relates broadly to a packaging machine and more particularly to a device for placing a disk-shaped rubber article in a tubular wrapper.
- 5 The device of the present invention is particularly useful in the packaging of collapsible articles. Although the device is described herein in conjunction with the packaging of thin, tubular, rubber articles, closed at one end, with the side 10 walls thereof rolled upon themselves to a point adjacent the closed end wall, it is not intended that it be so limited for the invention can be used for packaging numerous other types of articles. The wrapper for the article is preferably an open ended tubular member relatively smaller in diameter and axial length than the diameter of the article so that when the article and wrapper are assembled a portion of the article extends beyond the ends of the wrapper.
- 10 By the present invention there is provided a packaging device which includes, generally, a wrapper feeding assembly for conveying to and introducing tubular wrappers into successive chambers of a continuous transfer magazine as 15 they are presented to the wrapper feeding assembly, a receptacle for the articles and reciprocating means which pass through a wrapper, grip an article and draw it into the wrapper.
- 20 This invention relates generally to the type of device shown and broadly claimed in the copending application of Peter Jost, Serial No. 181,354 filed December 23, 1937.
- 25 In the drawings accompanying and forming a part of this specification, wherein similar reference characters denote corresponding parts:
- 30 Figure 1 is a fragmentary perspective view of a packaging device embodying the features of the present invention.
- 35 Figure 2 is a fragmentary top plan view of the device of Figure 1.
- 40 Figure 3 is a fragmentary longitudinal sectional view of the apparatus shown in Figure 1.
- 45 Figures 4 and 5 are fragmentary sectional views taken on the lines 4—4 and 5—5, respectively, 50 of Figure 3.
- 55 In the drawings there is illustrated apparatus embodying the present invention, including a substantially rectangular bed frame 10 supported on a frame-work comprising longitudinal members 11 and transverse members 12. Adjacent one end of the top of the bed frame is an elongated slot 13 having ways 14 mounted along each side thereof adapted to receive a reciprocating slide block 15. A bolt 16 threaded through the slide block 15 and extending through the slot 13 operatively connects the block to suitable reciprocating means, to be described, positioned below the top of the bed frame 10. The reciprocating block 15 has mounted thereon a pair of elongated spaced transfer fingers 17 and 18. The finger 17 is mounted in fixed position whereas the finger 18 is movable relative to the finger 17. Mounted in the path of the transfer fingers is a roller 19 engageable with the finger 18 and operable to effect the closing of the outer ends of the transfer 10 fingers.
- 20 Positioned adjacent the end of the outward stroke of the reciprocating transfer fingers is a cylindrical receptacle 20 for receiving, in stacked relation, disk-shaped articles A to be packaged, 25 as they are discharged from a continuous conveyor 21. An opening 22 is provided in the wall of the receptacle 20 through which the transfer fingers may enter the receptacle, grip an article and withdraw it from the receptacle.
- 25 Extending transversely of the bed frame 10 and mounted on the top thereof adjacent the receptacle 20 is a track 23 upon which rides a continuous chain 24 having a plurality of transfer members 25 secured thereto. Each of the members 25 is provided with an elongated slot constituting a magazine chamber 26 into which empty tubular wrappers are fed from a wrapper feeding assembly. Movement of the chain is controlled by sprockets 27 and 28 secured on shafts 29 and 30, 30 respectively, rotatably mounted in suitable bearings disposed along each side of the bed frame 10. A plate 25a is provided to cover the members 25 at the point where the transfer fingers are adapted to move through the magazine chambers of the 35 members.
- 30 The empty tubular wrappers are conveyed from a suitable hopper (not shown) to charging position by a feed tube 31 which serves to deposit successive wrappers into the end of a trough 32 defined by ways 33 secured to the top of the bed frame 10. Slidably mounted in the ways 33 is a plunger 34 which is operatively connected to the slide block 15 by link 35. The plunger 34 is adapted to introduce the empty wrapper disposed 40 in the trough 32 into the chamber 26 of the transfer member 25 aligned therewith as the slide 45 block 15 moves on its outward stroke. A plate 36 secured to the top of the bed frame covers the magazine chambers 26 at the point where the 50 wrappers are charged into the chamber by the plunger 34.
- 55 Supported beneath the top of the bed frame 10 are a pair of spaced bearings 37 and 38 having journaled therein a cam shaft 39 upon which is 55

keyed a spiral cam element 40. The cam shaft 39 may be rotated by any suitable means (not shown). The spiral cam 40 is positioned on the shaft 39 below the slot 13 and has formed therein a groove 41 in which rides a cam follower 42 freely mounted on the end of the bolt 16. Reciprocation of the slide block 15 together with the transfer fingers carried thereby is actuated by the cam 40, one revolution thereof effecting a complete reciprocation of the slide block 15.

The shaft 39 also has cam 43 mounted thereon which engages with a cam follower 44 carried on the lower end of a slideable rod 45, the other end thereof carrying the roller 19. The cam 43 is so formed and positioned on the shaft 39 that the roller 19 actuated thereby urges the transfer finger 18 toward the finger 17 at the end of their outward stroke and during the return stroke of the fingers, releasing the finger 18 just prior to the end of the return stroke, to release the article disposed between the ends of the fingers 17 and 18. The release of the article by the fingers is so timed that the article is deposited within a tubular wrapper positioned in one of the magazine chambers 26 of the members 25.

The mechanism for moving the continuous chain 24 along the track 23 to bring successive transfer members 25 into position for receiving a tubular wrapper and for inserting an article in a wrapper disposed in one of the members in timed relation with the reciprocation of the transfer finger includes ratchet wheels 46 and 47 mounted, respectively, on the shafts 29 and 30. Rotation of the shaft 29 is effected through an elongated pawl 48 engaging the ratchet wheel 46. The pawl 48 is pivotally connected to the end of a pivoted lever arm 49 supported from a longitudinally extending supporting member 50 by bracket 51. Mounted on the member 50 is a housing 52 in which is slidably mounted a slide block 53 the lower end of which is operatively connected to the free end of the lever arm 49. The upper end of the rod 52 is formed with a cam follower 54 which engages a cam element 55 mounted on the shaft 39. The ratchet wheel 47 mounted on the shaft 30 and engaged by a pawl 57 maintains a predetermined movement of the chain 24 during each rotation of the cam shaft 39 and assures that the magazine chambers are properly aligned with the transfer fingers. Suitable links 58 and 59 operatively connect the pawl 57 with the block 52 so that when the block 52 is depressed the pawl 57 is disengaged from the ratchet 46 to permit the pawl 48 to move the ratchet wheel 46 to rotate the shaft 29 thereby bringing the successive magazine chamber into alignment with the path of the reciprocating transfer fingers.

The operation of the apparatus described hereinabove may be briefly summarized as follows:—

The receptacle 20 and the magazine chambers 26 of the members 25 between the wrapper feeding assembly and the transfer fingers are filled, respectively, with articles and tubular wrappers. The cam shaft 39 is continuously rotating, and at the beginning of a cycle of operation, the slide 15 and transfer fingers 17 and 18 carried thereby are at the extreme left as viewed in Figures 1, 2 and 3. Rotation of the cam 40 moves the slide 15 to the right causing the transfer fingers 17 and 18 to traverse the magazine chamber 26 aligned therewith and a tubular wrapper in the chamber, and enter the receptacle 20 through the opening 22. The ends of the fingers 17 and 18 are open as they enter the receptacle 20 and positioned,

respectively, above and below the periphery of the lower-most article of the stack disposed therein. As the slide is moved on its outward stroke the plunger 34 operatively connected thereto lifts the end of the feed tube 31 and further movement of the slide causes the plunger 34 to project the empty tubular wrapper disposed in the trough 32 into the magazine chamber 26 aligned therewith.

At this point, which is the end of the outward stroke of the slide block 15, the cam 43 acts through the follower 44, rod 45, and roller 19 to move the finger 18 toward the finger 17. This movement of the roller 19 causes the ends of the transfer fingers 17 and 18 to grip the edge of an article in the receptacle. The cam 40 then starts the return stroke of the slide 15 during which movement the cam 43 maintains the fingers in gripping relation with the article. The transfer fingers 17 and 18 draw the article from the receptacle 20 and into the tubular wrapper disposed in the magazine chamber 26. The release of the article by the fingers is so timed that the article is substantially centered within the tubular wrapper. Immediately following the release of the article the cam element 55 is brought into play to depress the block 52 which effects the release of the pawl 57 from ratchet 46 and pivots the lever arm 49 thereby causing the pawl 48 to rotate ratchet 46 on shaft 29 which in turn effects movement of the chain 24 to bring the magazine chamber of the succeeding transfer member 25 into alignment with the path of travel of the reciprocating transfer fingers. The device is then in position to repeat the foregoing cycle of operation.

Having thus described the invention what we desire to obtain by Letters Patent is defined in the appended claims.

We claim:

1. An article packaging device comprising a receptacle for receiving disk-shaped collapsible articles to be packaged, a magazine having a plurality of movable chambered members for receiving open ended tubular wrappers for said articles and, reciprocating means mounted to move through a wrapper disposed in one of said chambered members and move one of said articles from said receptacle into and deposit it in said wrapper.

2. An article packaging device comprising a receptacle for receiving disk-shaped collapsible articles to be packaged, a magazine having a plurality of movable chambered members for receiving open ended tubular wrappers for said articles, reciprocating means mounted to move through a wrapper disposed in one of said chambered members and move one of said articles from said receptacle into and deposit it in said wrapper, and means for bringing successive members into alignment with said reciprocating means.

3. An article packaging device comprising a receptacle for receiving disk-shaped collapsible articles to be packaged, a movable magazine having a chamber for receiving an open ended tubular wrapper, reciprocating means mounted to move through a wrapper disposed in said chambered member and move one of said articles from said receptacle into and deposit it in said wrapper and means for moving said magazine across the path of travel of said reciprocating means to bring a wrapper into alignment with said reciprocating means.

4. An article packaging device comprising a

5 receptacle for receiving disk-shaped collapsible articles to be packaged, a magazine having a plurality of chambered members for receiving open ended tubular wrappers for said articles, reciprocating means mounted to move through a wrapper disposed in one of said chambered members and move one of said articles from said receptacle into and deposit it in said wrapper, and means for introducing an empty tubular 10 wrapper into one of said chambered members upon each reciprocation of said reciprocating means.

10 5. An article packaging device comprising a receptacle for receiving disk-shaped collapsible

articles to be packaged, a magazine having a plurality of chambered members for receiving open ended tubular wrappers for said articles, reciprocating means mounted to move through a wrapper disposed in one of said chambered members and move one of said articles from said receptacle into and deposit it in said wrapper, means for introducing a tubular wrapper into one of said chambered members upon each reciprocation of said reciprocating means, and 10 means for bringing successive members into alignment with said reciprocating means.
